[57] CLAIM

The ornamental design for a medical needle container, as shown and described.

DESCRIPTION

FIG. 1 is an isometric view of a medical needle container constructed in accordance with the present invention, a container door being shown in a closed orientation; FIG. 2 is an isometric view of the medical needle container shown in FIG. 1, but with the container door in an open orientation;

FIG. 3 is a top plan view of the medical needle container shown in FIG. 1;

FIG. 4 is a front elevation view of the medical needle container shown in FIG. 1, the rear elevation view being a mirror image thereof;

FIG. 5 is a right-side elevation view of the medical needle container shown in FIG. 1, the left-side view being a mirror image thereof; and,

FIG. 6 is a bottom view of the medical needle container shown in FIG. 1.
